(57) **CLAIM**

I claim the ornamental design for a dual cylinder air compressor, as shown.

DESCRIPTION

FIG. 1 is a front top perspective view of the dual cylinder air compressor.

FIG. 2 Is a left elevational view of the dual cylinder air compressor.

FIG. 3 is a right elevational view of the dual cylinder air compressor.

FIG. 4 is a front elevational of the dual cylinder air compressor.

FIG. 5 is a rear elevational view of the dual cylinder air compressor.

FIG. 6 is a top plan view of the dual cylinder air compressor; and,

FIG. 7 is a bottom plan view of the dual cylinder air compressor.
